UNITED STATES PATENT OFFICE.

ALBERT PAUL GILBERT, OF DURHAM, NORTH CAROLINA.

TOBACCO-HANGING MACHINE.

1,306,374.

Specification of Letters Patent. Patented June 10, 1919.

Application filed April 25, 1918. Serial No. 230,736.

To all whom it may concern:

Be it known that I, ALBERT P. GILBERT, a citizen of the United States, residing at Durham, in the county of Durham and 5 State of North Carolina, have invented a new and useful Tobacco-Hanging Machine, of which the following is a specification.

This invention has reference to tobacco hanging machines, whereby bundles of tobacco are automatically strung upon sticks or rods preparatory to placing such sticks with the bundles of tobacco thereon in drying compartments.

It is the customary procedure after the 15 tobacco is harvested to hang the plants or stalks in their entirety to dry out the leaves and fix the color. Then, at the convenience of the planter, the leaves are stripped from the stalks and graded as to size, color and 20 type, the procedure being, in the tobacco industry, called grading. The leaves are then tied into bundles of twelve or fifteen, more or less, with one leaf wrapped around the butt end of the bundle of leaves to hold 25 them in the bundle form. Such bound mass of leaves is called a bundle or hand. The bundles are then sold in piles at the warehouse. All this is preliminary to this invention, in accordance with which latter the 30 bundles of tobacco are taken by the purchaser to plants built for the purpose in which the tobacco is redried, the bundles being put separately on sticks about five feet long with the bundles hanging one after the 35 other astride the stick. Such hung bundles are put in redrying machines and carried through a process which determines the amount of moisture which is necessary to 40 cure the tobacco and preserve it, after which the tobacco is packed and stored for about two years before being manufactured.

Prior to this invention the hanging of the bundles on the sticks has been entirely a manual procedure, but by means of the 45 invention the procedure is made automatic and the amount of tobacco strung upon the stick is predetermined, the only part of the whole operation which may require any handling of the tobacco being the placing 50 of the bundles at the receiving end of the machine.

The impaling sticks are automatically and successively placed in position, and then the bundles of tobacco are forced one after the 55 other upon a placed stick until the required amount has been so placed, whereupon the

filled stick, that is, one having the predetermined amount of tobacco thereon, is discharged from the machine, such operation temporarily stopping the automatic feed of 60 the tobacco toward the stick zone, starting mechanism previously quiescent, resulting in the discharge of the filled stick, and placing another stick in position to receive the predetermined amount of tobacco, after 65 which the initial operation is again established to be repeated indefinitely.

The invention will be best understood from a consideration of the following detailed description taken in connection with the accompanying drawings forming part 70 of this specification, with the understanding, however, that the invention is not confined to any strict conformity with the showing of the drawings but may be changed and 75 modified so long as such changes and modifications mark no material departure from the salient features of the invention as expressed in the appended claims.

In the drawings:—

Fig. 1 is an elevation of a machine embodying the invention, the view being taken from the discharge side of the machine.

Fig. 2 is an elevation of the machine from the opposite side thereof, some parts being 85 broken away.

Fig. 3 is a plan view of the machine.

Fig. 4 is a section on the line 4—4 of Fig. 1.

Fig. 5 is a section on the line 5—5 of 90 Fig. 1, but drawn on a larger scale.

Fig. 6 is a section on the line 6—6 of Fig. 3, but drawn on a larger scale and omitting some parts.

Fig. 7 is a section on the line 7—7 of 95 Fig. 3, but drawn on a larger scale and omitting some parts.

Fig. 8 is a detail section on the line 8—8 of Fig. 1, but drawn on a larger scale.

Fig. 9 is a detail view of a portion of the 100 stick holding reel showing a temporary holding means for the reel, some parts being indicated in section.

Fig. 10 is a detail section of a cam used in the structure.

Referring to the drawings, there is shown a frame 1 of suitable shape and suitably constructed to support various mechanisms to which reference is hereinafter made. Since the framework may be variously 110 formed and constructed of various materials, no special reference is made thereto.

Mounted on the framework are spaced drums 2, 3 carrying an endless conveyer belt 4 having its upper run supported upon idler rollers 5, and along one face of the 5 conveyer belt in elevated relation thereto is an abutment board 6 so that bundles 7 of tobacco may be placed upon the conveyer 4 and caused to properly travel by engagement with the abutment board 6.

10 These bundles are composed of masses of tobacco leaves tied together at one end by another leaf or leaves to produce a butt 8, the remainder of the leaves being loose.

The machine is provided with a roller 9 having its periphery roughened or suitably arranged to grip the bundles, the roller 9 being spaced above one end of the drum 2 so that as the conveyer 4 carries the bundles along with it they ultimately pass between 15 the roller 9 and the drum 2 and are gripped between these two parts, thus being forcefully propelled. In the path of the propelled bundles is a stick or rod 10 having the ends 11 sharpened or pointed. The stick 20 10 constitutes an impaling stick which, by suitable devices to be described, is presented and held in the path of the bundles 7 immediately adjacent to the butts 8 so that as the bundles 7 are positively moved under 25 the action of the roller 9 and drum 2 they are forced upon the stick in succession until a certain amount of the tobacco becomes impaled upon the stick, whereupon, by mechanism to be described, the feeding is 30 stopped and the stick is transferred to another position and discharged from the machine or moved to a point of discharge.

The stick 10, when in position to receive the bundles 7, is carried by a reel 12, best 35 shown in Figs. 5, 6 and 8, although appearing in other figures of the drawings. The reel comprises two heads 13, 14 respectively, joined and spaced apart by a neck or hub 15. The heads 13 and 14 have matching 40 peripheral recesses or pockets 16 so disposed that two matching recesses or pockets will receive a stick 10 and sustain it in suitable relation to the longitudinal axis of the reel, with the stick having one pointed end 45 in the pocket in the head 13 and the other pointed end projecting beyond the head 14 into close relation to the drum 2 and feeding roller 9. The reel is mounted on a shaft 17 supported in journal bearings carried by 50 posts 18, 19 respectively, of the main frame. The head 13 of the reel carries pairs of guides 20 on the face toward the head 14 on the reel, and on a cross bar 21 of the main frame there is mounted a pin 22 situated to enter between a pair of guides 20 when the reel is in a certain position to be referred to so as to temporarily hold or lock the reel against rotation, the reel being capable of movement lengthwise of 55 the shaft 17 but may be held thereto in a

manner causing the reel to rotate with the shaft.

Adapted to the heads 13 and 14 are hoods or caps 23, best shown in Figs. 5, 6 and 8 but appearing in others of the figures. The 70 hoods 23 are alike and are connected together by cross bars 24 which may be cast in one piece with the hoods or these parts may be otherwise formed. The hoods extend partially about the upper portions of 75 the heads 13 and 14, and one hood 23 has a side flange 25 extending partially over that face of the head 13 remote from the head 14 so as to form an abutment for the rods 10 especially when the rods are in position 80 to receive the bundles of tobacco, wherefore, the flange 25 receives the thrust of the rod during the impaling operation. The hoods each have an arm 26 overriding a discharge chute 27 leading from a reservoir 28 85 for the rods 10, this reservoir being carried by uprights 29 of the main frame to one side of the rod-carrying reel. The arms 26 ride upon guide rods 30, 31 mounted upon the discharge chute 27 so that the reel may 90 be moved axially for a purpose to be described and the hoods 23 will participate in such axial movement, always covering the heads 13 and 14 from a point closely adjacent to the outlet end of the chute 27 to a 95 point beyond the top of the reel with the latter rotating clockwise as seen in Fig. 5, or counter-clockwise as seen in Fig. 8. In this way a quarter turn of the reel which, at a period of rest, has matching peripheral 100 notches 16 opposite the outlet end of the chute 27 and therefore lodging a rod 10, will carry the latter to a position 90° distant therefrom with the rod 10 then at the uppermost point of its travel with the reel. 105 When this occurs another rod lodges in the next succeeding pair of matching notches or pockets 16 and a second quarter turn of the reel will repeat the operation just described with relation to the second named 110 rod, while the first named rod is carried to a point 180° distant from the receiving point and this rod is in the meantime discharged from the reel by gravitation, falling upon tracks 32 declining to one side of the machine and supported upon posts 33 or other suitable parts of the main frame, one of the tracks 32 best appearing in Fig. 5, and these tracks being also shown in Fig. 3 and others of the figures.

The hood structure has fast thereto another rod 34, best seen in Fig. 6 although shown in Fig. 1 and others of the figures, and this rod has a free end closely approaching the receiving end of a placed impaling stick where the rod 34 is provided with an elastic tongue 35 so arranged as to permit the bundles 7 to move along the impaling stick in the feeding operation, but preventing any return movement of these bundles. 130

When a sufficient number of bundles 7 has been moved upon the impaling stick or rod 10 the first bundle to be impaled ultimately comes in contact with a finger 36 carried by a block 37 adjustably held on a link 38 by a set screw 39 or otherwise, this structure being best shown in Fig. 7 but appearing in others of the figures. The link 38 is mounted to rock upon a pin or bracket 40, projecting through an elongated slot 41 in the link, since in the operation of the latter the link both rocks upon the pin 40 and moves lengthwise thereof. The link 38 at the end remote from the block 37 has pivoted thereto a bar 42 in pendant relation to the link and extending through a guide 43, permitting the bar 42 to move lengthwise and sidewise, the latter movement being restricted to one direction by the guide 43. At an appropriate point on the bar 42 is a latch tooth 44 in position to engage one of the teeth of a ratchet wheel 45 mounted on a shaft 46 constituting the drive shaft of the machine and extending beyond the same side of the machine on which the reservoir 28 is located. The bar 42 is engaged by a spring 47 normally maintaining the tooth 44 out of the path of the teeth of the ratchet wheel 45 but yieldable to properly applied force. The end of the bar 42 remote from the link 38, this being the lower end of the bar in the showing of the drawings, is connected to a bell crank lever 48, best seen in Fig. 4, which lever is supported by a bracket 49 on a portion of the main frame and is connected by a rod 50 to a junction bar 51 between two clutches 52, 53 respectively, these clutches appearing in Figs. 3 and 4, and which clutches may be of ordinary type and hence requiring no special description. The clutch 52 is arranged to couple a pinion 54 to the drive shaft 46 and this pinion is in mesh with a gear wheel 55 on a shaft 56 secured to the drum 2 for rotating it. The clutch 53 is arranged to couple a pinion 57 to the drive shaft and this pinion is in mesh with a gear wheel 58 on a countershaft 59 mounted in an appropriate portion of the main frame. The shaft 59 serves the purpose of a cam shaft having two cams 60 and 61 fast thereto or these cams may constitute a single member, as for instance a single casting, with appropriate cam portions. The cams 60 and 61 appear in Figs. 1, 2, 3 and 10. In the particular showing of the drawings the cam 60 has a cam groove 62 in one face in which groove there engages a roller 63 on one end of a slidable bar 64 mounted in a bearing 65 on an appropriate part of the main frame. This bar has a continuation 66, best shown in Figs. 1 and 5, and terminates in a fork 67 engaging in a grooved collar 68 fast to the rod-carrying reel, so that with the groove 62 of proper shape the reel is caused

to reciprocate in timed relation to the operation of other parts of the machine for a purpose which will hereinafter appear.

In the path of the cam 61 is one end of a rock lever 69 carried by a bracket 70 upon an appropriate part of the frame and the other end of the lever engages a reciprocating latch rod 71 which, when the reel is at one limit of its axial travel has a latch tooth 72 in position to engage a suitable one 73 of a circular series of projections or studs 73 on the head 13 of the reel, the parts being arranged so that each time the cam 61 rotates the lever 69 will reciprocate the latch member 71 and cause the 90° movement of the reel, which movement and its effects have already been described.

The power shaft 46 is provided with a pulley 74 by means of which power may be applied to the shaft by a belt 75 or in any other manner, the pulley and belt being considered as indicative of any suitable driving power. The shaft 59 carries a cam 76 having a cam projection 77 on one face in the path of which is a lever 78 connected at the end remote from the cam with the clutches 52 and 53, these clutches being oppositely acting clutches so that when the clutch 52 is active the clutch 53 is out of action and vice versa.

In order to drive the roller 9 the drive shaft 46 carries a sprocket pinion 79 from which there extends a sprocket chain 80 to an idler sprocket pinion 81 driving another sprocket pinion 82 which in turn drives a sprocket chain 83 engaging about a sprocket pinion 84 on a shaft 85 on which the drum 9 is mounted. The shaft 85 is carried by bearings 86 of a character permitting the drum 9 to rise and fall to accommodate varying thicknesses of the butts 8 of the bundles 7 and so maintain driving engagement therewith without injury thereto.

Certain phases of the operation have been referred to hereinbefore but these parts of the operation may be briefly repeated to give a connected account of the action of the machine.

It may be assumed that the drive shaft 46 is running and that the clutch 52 is in position to couple the drive shaft with the drum 2, thus causing the conveyer belt 4 to travel. The roller 9 being at all times connected with the drive shaft is also in motion so that where adjacent to the drive belt it is traveling in the same direction. It may be further assumed that an impaling stick 10 is properly placed on the reel heads 13 and 14 of the reel 12. Now, bundles 7 are placed upon the conveyer 4 and positioned by being moved against the board 6. These bundles ultimately come under the roller 9 and are fed by the latter toward the stick or rod 10 which pierces the bundles adjacent to their butts 8 where the leaves are easily

separated. The bundles pass the spring finger 35 as they progress along the stick 10, the bundles on leaving the conveyer turning by gravity on the stick, which is of round or 5 other suitable cross section for the purpose, to a position where the loose leaf ends hang pendants, there being nothing in the way in the machine to prevent such position of the bundles. The impaled bundles accumu- 10 late in side contact on the stick, each freshly impaled bundle pushing the preceding bundles along the stick until the first bundle impaled reaches the finger 36, whereupon, a further accumulation of bundles causes the 15 finger to yield and the link 38 to move with it, thus rocking the bar 42 so as to bring the tooth 44 into the path of one of the teeth of the ratchet wheel 45. The result of this is that the finger 36 is rocked out of the way 20 of the bundles on the stick 10 and at the same time rocks the bell crank lever 48 to an extent shifting the clutch 52 out of action and the clutch 53 into action. This disconnects the driving mechanism for the con- 25 veyer from the drive shaft so that movement of the conveyer is arrested and no more bundles are fed upon the stick 10 which is then loaded. The shaft 59 is put into motion by being coupled to the drive shaft 30 through the pinion 57 and gear wheel 58 and the cams 60 and 61 are set in motion. These cams cause first an axial movement of the reel 12 away from the conveyer belt and a corresponding movement of the stick 10 35 and rod 34 so that the loaded stick retreats from its first position. As soon as the head 13 is in position to bring the pins or studs 73 into the path of the tooth 72 the cam 61 comes into action, thereby rocking the lever 40 69 in the direction to cause the tooth 72 to rotate the reel 12 a quarter revolution, thus bringing the loaded stick 10 to a position where it is out of the path of the hoods 23, whereupon, the stick 10 will gravitate from 45 the reel onto the tracks 32 and so move by gravity, these tracks slanting to the discharge part of the machine. The quarter rotation of the reel has caused a new stick 10 to be presented into line with the space 50 between the roller 9 and conveyer 4 and when this is accomplished the cam 60 returns the reel to the first position. The groove 62 of the cam 60 is so shaped that 55 during the first part of its movement it actuates the reel away from the conveyer 4, then holds it in such position while the reel is being given a quarter rotation and then returns it to the first position ready for the loading of the new stick with bundles of 60 tobacco. By the time this has been accomplished the projection 77 of the cam 76 has reached the lever 78 and rocked the latter to an extent moving the clutch 52 into active 65 position and the clutch 53 out of active position, thus again starting the conveyer and

causing the movement of the bundles of tobacco to and onto the impaling stick already placed.

The action of the machine is entirely automatic in placing the bundles of tobacco on the stick, presenting new sticks and discharging the loaded sticks from the machine. 70

When the sticks loaded with bundles of tobacco are hung up in a drying chamber the bundles must be spread apart lengthwise 75 of the stick in order to properly dry. To provide for this sticks are only partially filled with bundles of tobacco while in the machine, a material portion of each stick occupying the reel 12 so as to give ample room 80 for spreading the bundles along the stick after being discharged from the reel, or after being taken from the machine.

The purpose of positively, though temporarily, locking the reel against rotation when 85 in the forward or active position, is to firmly hold the stick at the time of being loaded with bundles of tobacco.

What is claimed is:—

1. A machine for hanging tobacco in the 90 form of bundles thereof with the leaves bound together at one end, comprising a frame adapted to rest upon a fixed support, a conveyer on the frame for receiving the bundles deposited thereon with the bound 95 ends all directed toward and adjacent to one side of the conveyer, means for presenting and holding impaling sticks adjacent to the discharge end of the conveyer and in the line of travel of the bound ends of the bundles, and means responsive to the accumulation 100 of a predetermined quantity of tobacco on the stick for temporarily arresting the feed of the bundles onto the stick, and during the period of rest causing the discharge 105 of the filled stick and the presentation of an empty stick into the path of travel of the bound ends of the bundles.

2. A machine for hanging tobacco in the 110 form of bundles with the leaves bound together at one end, comprising a fixed frame, receiving means on said frame for the bundles of tobacco, feeding means for the bundles deposited on said receiving means by hand, and means for automatically presenting impaling sticks in the path of the bound ends of the bundles.

3. In a machine for hanging tobacco in the 115 form of bundles with the leaves bound together at one end, means for feeding the 120 bundles of tobacco, spaced means for supporting impaling sticks each near one end with the other end free and directed toward the delivery end of the feeding means, and means responsive to the accumulation of 125 bundles of tobacco in contact upon the end of the stick presented toward the feeding means for causing the discharge of the stick from the path of the ends of the bundles to be impaled, the accumulation of contacting 130

bundles on a stick being less than the capacity of the stick, whereby sufficient space remains on a filled stick to permit the subsequent separation of the impaled bundles 5 along the stick.

4. In a machine for hanging bundles of tobacco with the leaves bound together at one end, means for conveying the bundles substantially horizontally through a substantially horizontal path of travel, and automatic means for presenting impaling sticks or rods one at a time at the discharge end of the conveying means and located to pierce the bundles of tobacco closely adjacent to the bound ends, the sticks or rods being of a cross section for the gravitation of the bundles of tobacco on the rods from a substantially horizontal position to a pendant position.
- 20 5. A hanging machine for bundles of tobacco each made up of leaves bound together at one end, comprising a stationary frame, a conveyer on the frame for the bundles having a substantially horizontal run to support the bundles in a substantially horizontal position with the length of the bundles transverse to the line of travel of the conveyer, feeding means associated with the conveyer at the discharge end thereof and located to engage the bound ends of the bundles, and automatic means for presenting impaling sticks or rods into the path of the bundles adjacent to the bound ends for the forcing of the bundles onto the impaling sticks by the feeding means.

6. A hanging machine for bundles of tobacco each made up of leaves bound together at one end, comprising a stationary frame, a conveyer on the frame for the bundles having a substantially horizontal run to support the bundles in a substantially horizontal position with the length of the bundles transverse to the line of travel of the conveyer, feeding means associated with the conveyer at the discharge end thereof and located to engage the bound ends of the bundles, and automatic means for presenting impaling sticks or rods into the path of the bundles adjacent to the bound ends for forcing the bundles onto the impaling sticks, said impaling sticks being of a cross sectional shape to permit the turning thereon by gravity of the impaled bundles to a pendant position, and the machine being free beneath the presented sticks from impediment to such movement of the bundles.

7. In a machine for hanging bundles of tobacco each composed of a mass of tobacco leaves tied together at one end to there produce a butt, comprising a stationary frame, an endless, substantially horizontal conveyer for carrying the bundles of stalks in substantially horizontal position and arranged transversely of the line of travel of the conveyer with the butt ends of the bundles all

at the same side of the conveyer, a feeding roller associated with the conveyer at the discharge end thereof and arranged at the same side of the conveyer as the butt ends of the stalks to grip said butt ends of the stalks in conjunction with the conveyer to forcefully discharge the stalks, and automatic means for presenting impaling sticks or rods in the path of the discharging stalks adjacent to the bound ends thereof for piercing and holding the stalks.

8. In a tobacco hanging machine, means for feeding bundles of tobacco, means for presenting impaling devices successively in the path of traveling bundles to receive said bundles, means for causing the discharge of a filled stick and the presentation of an empty stick into position to receive the bundles, and means responsive to the accumulation of bundles in side contact on a stick to stop the feed of bundles while the full stick is discharged and the succeeding empty stick is presented into position to receive the bundles.

9. In a tobacco hanging machine, means for feeding bundles of tobacco in a path transverse to the length of the bundles, rotatable means for holding an impaling stick or rod parallel to and moving it orbitally with respect to the axis of rotation of the rotatable means into the path of the bundles, and means for forcing the bundles in succession onto the positioned impaling stick or rod.

10. In a tobacco hanging machine, a rotatable reel having peripheral receptacles for impaling sticks or rods, whereby the sticks may receive orbital movement by rotation of the reel with the sticks held parallel with the axis of such orbital movement, and means for forcing a succession of bundles of tobacco onto a stick carried by the reel when the stick is in one position of its orbital movement.

11. In a tobacco hanging machine, the combination with an impaling stick, of a fixed rod arranged alongside of and extending in the same direction as the stick and having its free end terminating short of the free end of the stick, and at said free end the rod being provided with a tongue arranged to permit bundles to move along the impaling stick onto the latter but preventing any return movement of the bundles.

12. In a tobacco hanging machine, means for holding an impaling stick, means for feeding a succession of bundles of tobacco onto the stick, and means responsive to an accumulation of bundles in contact on the stick to cause the stopping of the feed and the discharge of the loaded stick.

13. In a tobacco hanging machine, means for propelling bundles of tobacco, means for presenting impaling devices successively into the path of the traveling bundles, with said

- presenting means movable lengthwise of the line of travel of the bundles, means for starting and stopping the feed of the bundles, means for moving the presenting means lengthwise of the line of travel and for moving the presenting means in another direction, and tripping means responsive to an accumulation of bundles upon a presented impaling device for causing the stopping of the feed, the movement of the presenting means lengthwise of the impaling device and the discharge of a loaded impaling device.
14. In a tobacco hanging machine, a conveyer for bundles of tobacco, a feeding roller positioned to engage the bound ends of the bundles propelled by the conveyer, and a reel for carrying impaling sticks, said reel being related to the conveyer and feed roller to present the sticks end-on to the traveling bundles in position to receive the bundles from the feed roller.
15. In a tobacco hanging machine, a conveyer for bundles of tobacco, a feeding roller positioned to engage the bound ends of the bundles propelled by the conveyer, a reel for carrying impaling sticks and related to the conveyer and feeding roller to present the stick end-on to the traveling bundles in position to receive the bundles from the feeding roller, and a holder for association with a presented impaling stick and having a latch portion extended lengthwise of the stick to temporarily retain the bundles loaded on said stick.
16. In a tobacco hanging machine, a conveyer for receiving bundles of tobacco, a feed roller associated with and located at the discharge end of the conveyer, and a reciprocable reel for carrying impaling sticks and movable to receive and present impaling sticks to the discharge end of the conveyer adjacent to the feed roller for receiving the bundles of tobacco propelled by the feed roller.
17. In a tobacco hanging machine, a conveyer for receiving bundles of tobacco, a feed roller associated with and located at the discharge end of the conveyer, and a reciprocable reel for carrying impaling sticks and movable to receive and present impaling sticks to the discharge end of the conveyer adjacent to the feed roller for receiving the bundles of tobacco propelled by the feed roller, said machine being provided with a reservoir for sticks positioned to deliver the sticks one at a time to the reel, and means for moving the reel to withdraw a loaded stick from loading position and move the reel to discharge the loaded stick therefrom.
18. In a tobacco hanging machine, means for feeding bundles of tobacco, a reel for holding impaling sticks and associated with the feeding means, a reservoir for the im-

paling sticks associated with the reel and 65 related to the reel to feed sticks, near one end of the latter, to the reel, means for reciprocating the reel to move the sticks into bundle-receiving relation to the feeding means and to withdraw them therefrom, 70 and means for imparting rotative movement to the reel to carry a stick from the reservoir into the line of travel of the bundles and to discharge a loaded stick from the reel.

19. In a tobacco hanging machine, means for feeding bundles of tobacco, a rotatable and reciprocable reel associated with the feeding means and arranged to receive and hold impaling sticks, means for feeding impaling sticks to the reel, means for rotating the reel to present a stick into the line of travel of the bundles of tobacco propelled by the feeding means, means for reciprocating the reel to present the sticks into position 85 to receive the bundles of tobacco and to withdraw the loaded sticks therefrom, and means responsive to an accumulation of bundles of tobacco upon an impaling stick to throw the feeding means out of action and set the 90 means for reciprocating and the means for rotating the reel into action.

20. In a tobacco hanging machine, means for feeding bundles of tobacco, a rotatable and reciprocable reel associated with the 95 feeding means and arranged to receive and hold impaling sticks, means for feeding impaling sticks to the reel, means for rotating the reel to present a stick into the line of travel of the bundles of tobacco propelled 100 by the feeding means, means for reciprocating the reel to present the sticks into position to receive the bundles of tobacco and to withdraw the loaded sticks therefrom, and means responsive to an accumulation of bundles of tobacco upon an impaling stick to throw the feeding means out of action and set the means for reciprocating and the 105 means for rotating the reel into action, the reel having means associated therewith for holding impaled bundles upon the impaling stick during the withdrawal of the stick from bundle-receiving position with respect to the bundle feeding means.

21. In a tobacco hanging machine, means 115 for feeding bundles of tobacco, a reel for receiving and carrying impaling sticks, a reservoir for the sticks associated with the reel to feed the sticks thereto, hood devices associated with the reel to hold the sticks to 120 the reel during transfer by the reel from one position to another, one of the hoods having abutting means for an active impaling stick, means for reciprocating the reel, means for rotating the reel, and means responsive to 125 accumulated bundles upon a loaded stick for stopping the feed of bundles and causing the reciprocation and rotation of the reel to

present an empty stick into position to be loaded and discharge a loaded stick from the reel.

22. In a tobacco hanging machine, means for feeding bundles of tobacco, a reel for receiving and carrying impaling sticks, a reservoir for the sticks associated with the reel to feed the sticks thereto, hood devices associated with the reel to hold the sticks to the reel during transfer by the reel from one position to another, one of the hoods having abutting means for an active impaling stick, means for reciprocating the reel, means for rotating the reel, and means responsive to accumulated bundles upon a loaded stick for stopping the feed of bundles and causing the reciprocation and rotation of the reel to present an empty stick into position to be loaded and discharge a loaded stick from the reel, the hood device participating in the reciprocatory movements of the reel and provided with holding means for retaining bundles on a loaded stick during the withdrawal of the stick from loading position.

23. In a tobacco hanging machine, a rotatable and reciprocable reel, means on the reel for carrying impaling sticks, and temporary locking means for holding the reel against rotation at one limit of its reciprocatory movement.

24. In a tobacco hanging machine, a rotatable and reciprocable reel for carrying impaling sticks, and means for rotating the reel, comprising a latch member and matching parts on the reel arranged to be brought into engagement at one limit of reciprocatory travel of the reel, and means for operating the latch member when the reel is in

position to be engaged by said latch member.

25. In a tobacco hanging machine, a reciprocable and rotatable reel for carrying impaling sticks, and means for reciprocating the reel and rotating it in timed relation, comprising cams and connections therefrom, one cam and its connections causing the reciprocation of the reel during a portion of the movement of the cam and holding the reel during the remainder of the movement of the cam, and the other cam causing a partial rotation of the reel at one limit of its reciprocatory movement and then holding the reel against rotation until the reel is moved in the other direction of reciprocation.

26. In a tobacco hanging machine, a reciprocable and rotatable reel for carrying impaling sticks, and means for reciprocating the reel and rotating it in timed relation, comprising cams and connections therefrom, one cam and its connections causing the reciprocation of the reel during a portion of the movement of the cam and holding the reel during the remainder of the movement of the cam, and the other cam causing a partial rotation and then holding the reel against rotation until the reel is moved in the other direction of reciprocation, said reel having associated therewith temporary lock means for holding it against rotation when at the other limit of its reciprocatory movement.

In testimony, that I claim the foregoing as my own, I have hereto affixed my signature.

ALBERT PAUL GILBERT.
